UNITED STATES PATENT OFFICE.

FRANKLIN M. HOLDER, OF OXFORD, LOUISIANA.

WELL DRILL.

Application filed March 8, 1926. Serial No. 93,319.

This invention relates to well drills and one object of the invention is to so construct the drill that if one of the longitudinally extending sections of the drill works out of engagement with a companion section it will be prevented from becoming entirely detached from the companion section. It often happens that when drilling a well the sections of the drill will become detached and the lower portion has to be removed by a fishing operation. This is very difficult to accomplish and it is often necessary to abandon the well.

Another object of the invention is to so form the means for preventing entire detachment of the drill sections that the passage of slush upwardly through the hollow drill will not be interfered with.

Another object of the invention is to so form the improved connecting means for the drill sections that it may be readily applied to drills of a conventional construction.

This invention is illustrated in the accompanying drawing, wherein—

Figure 1 is a longitudinal sectional view through the lower portion of the improved drill, and

Fig. 2 is a transverse sectional view taken on the line 2—2 of Fig. 1.

The well drill forming the subject-matter of this invention includes a shaft having the usual tubular sections 1 which are detachably connected at their adjacent ends by couplings 2. It will be understood that any number of tubular shaft sections 1 may be provided according to the depth of the well, and that these sections are to be joined together by the couplings as the depth of the well increases. The adjacent end portions of the sections 1 are threaded externally and preferably tapered, as shown at 3, and are screwed into the internally threaded end portions 4 of the coupling which connects them. The lowermost shaft section has its lower end internally threaded, as shown at 5, to receive the threaded shank 6 of the drill bit 7. The drill bit is of a conventional construction, except that its upper end is reduced and threaded to form a neck 8 which is disposed in spaced relation to the walls of the shaft section. The usual longitudinally extending slush passages 9 are formed in the bit so that slush may be forced through the drill as indicated by arrows in Fig. 1 into the bottom of the well and carry the

cuttings upwardly about the drill shaft to the top of the well in the usual manner. The couplings are of a duplicate construction and each has its intermediate portion 10 internally thickened and formed with threaded sockets 11 which communicate through the bore 12 so that slush which enters the lower section 1 may pass upwardly through successive shaft sections until it reaches the top of the shaft. It will, therefore, be seen that the drill may be operated in the usual manner.

Nipples 13 and 14 are screwed into the sockets 11 of each of the couplings 2 and a similar nipple 15 has threaded engagement with the neck 8 of the drill bit 6. These nipples are each formed with a head 16 having an opening 17 formed axially therein, the opening 17 of the nipple 14 being formed with smooth walls and the opening of the nipples 13 and 15 being threaded. One or more side openings or ports 18 are formed in each nipple and the nipple 13 is formed with openings 19 which are located above its openings 18 and close to its head 16. By having the nipples formed with the openings 18, the slush may readily pass downwardly through the hollow shaft from one section to another and through the passages 9 into the bottom of the well. The swivel rods 20 which serve to prevent complete separation of the shaft sections extend longitudinally in the shaft sections and each has its lower end portion threaded, as shown at 21, and its upper end portion formed with an enlarged head 22. The threaded lower end portions of the swivel rods shown in the illustration are screwed into the threaded openings 17 of the nipples 13 and 15 and are prevented from being removed therefrom by cotter keys 23. The cotter key of the lower rod 20 is inserted into the opening formed therein through one of the ports 18 of the nipple 15 and the cotter key carried by the second rod 20 is inserted in the opening formed therein through one of the openings 19 and has the free ends of its arms moved to a locking position by a screwdriver or other similar instrument inserted through the second opening 19. It will, therefore, be seen that the swivel rods will be securely held in engagement with the nipples 13 and 15 but may be released therefrom when desired. The upper end portions of the swivel rods extend through the unthreaded openings 17 of the nipples 14

carried by the various couplings and while the rods may have limited sliding movement in these couplings they are prevented from moving downwardly out of engagement with the couplings by their heads 22. It will, of course, be understood that the rods are passed downwardly through the couplings 14 and have their lower ends then screwed into engagement with either the coupling 15 or a cooperating coupling 13.

When the drill is in use, the sections forming the hollow shaft and the bit are assembled as shown in Fig. 1 and as the well increases in depth additional shaft sections are applied to its upper end above the ground. During the drilling operation, the drill is rotated in the hole so that a hole is formed which is substantially circular in cross section. This rotary movement takes place while the drill is being reciprocated in the well. It often happens that during the drilling of a well the tubular shaft forming sections will become detached from the couplings and the lower portion of the drill will remain in the bottom of the well. If they become detached while the drill is being lifted, the lower portion will drop and often bend when it strikes the bottom of the well. This causes it to be jammed in the well and even if its upper end can be engaged with a fishing tool it is impossible to extract it and the well must be abandoned. Even if the released lower end portion of the drill is not bent and wedged in the well, it is often impossible to engage it with a fishing tool. By having the drill formed, as shown in Fig. 1, a drill is prevented from dropping in a well when one section works out of engagement with the coupling connecting it with an adjacent section as the swivel rod may only move downwardly the distance between its head 22 and the head 16 of the nipple 14 in which it is seated. Therefore, the shaft section cannot become entirely released from the coupling connecting it with an upper shaft section and there will be no danger of the lower portion of a drill dropping in a well and ruining the well.

Having thus described the invention, I claim:

1. A well drill comprising tubular sections disposed one above another, a coupling disposed between and detachably engaged with adjacent ends of said sections, a bit detachably engaged with the lower end of the lowest one of said tubular sections, nipples detachably engaged with said bit and coupling and extending into adjacent end portions of said tubular sections, and means extending through said tubular sections and engaged with said nipples to limit movement of the tubular sections away from each other when detached from said coupling and prevent complete separation thereof.

2. A well drill comprising tubular sections disposed one above another and having threaded end portions, a coupling sleeve having threaded engagement with adjacent ends of said sections and having its intermediate portion internally thickened and threaded, a bit in threaded engagement with the lower end of the lowest one of said tubular sections, nipples screwed into engagement with said bit and the internally threaded intermediate portion of said coupling sleeve and extending into the end portions of said tubular sections, and means extending through said tubular sections and engaged with said nipples to limit movement of the sections and bit away from each other when detached from said coupling sleeves and prevent complete separation thereof.

3. A well drill comprising tubular sections disposed one above another and having threaded end portions, a coupling sleeve having threaded engagement with adjacent ends of said sections and having its intermediate portion internally thickened and threaded, a bit in threaded engagement with the lower end of the lowest one of said tubular sections, nipples screwed into engagement with said bit and the internally threaded intermediate portion of said coupling sleeve and extending into the end portions of said tubular sections, and swivel rods extending longitudinally in said tubular sections and each having one end detachably engaged with a nipple and its other end slidably and rotatably engaged with a nipple and provided with means for limiting its sliding movement.

4. A well drill comprising tubular sections disposed one above another and having threaded end portions, a coupling sleeve having threaded engagement with adjacent ends of said sections and having its intermediate portion internally thickened and threaded, a bit in threaded engagement with the lower end of the lowest one of said tubular sections, nipples screwed into engagement with said bit and the internally threaded intermediate portion of said coupling sleeve and extending into the end portions of said tubular sections, and swivel rods extending longitudinally in said tubular sections and each having one end in threaded engagement with a cooperating nipple and its other end extending into a cooperating nipple and slidably and rotatable therein and provided with a head to engage the nipple and limit sliding movement in one direction and thereby limit movement of the tubular sections away from each other when detached from said coupling sleeves.

5. A well drill comprising tubular sections disposed one above another, a coupling disposed between and detachably engaged

with adjacent ends of said sections, a bit
detachably engaged with the lower end of
the lowest one of said tubular sections and
formed with a slush passage, hollow nip-
5 ples detachably engaged with said coupling
and extending into said tubular sections
and communicating with each other through
the coupling and formed with side open-
ing for communication with the tubular sec-
10 tions, a similar nipple detachably engaged
with the inner end of said bit and com-

municating with the slush passage thereof
and interior of the lowest tubular section,
and swivel rods extending longitudinally in
said tubular sections and each having one
end detachably engaged with a cooperating
nipple and its other end slidably and rota-
bly received in a cooperating nipple and
provided with a head to limit its sliding
movement.

In testimony whereof I affix my signature
FRANKLIN M. HOLDER. [L.S.]
